JAMES R. RISHEBEGAR, OF BRADDOCK, PENNSYLVANIA.

SHIELD FOR FURNACES.

1,287,104.

Specification of Letters Patent. Patented Dec. 10, 1918.

Application filed April 17, 1918. Serial No. 229,116.

To all whom it may concern:

Be it known that I, JAMES R. RISHEBEGAR, a citizen of the United States, residing at Braddock, in the county of Allegheny and State of Pennsylvania, have invented a new and useful Shield for Furnaces, of which the following is a specification.

This invention relates to shields for furnaces, and its object is to provide a shield which may be introduced into a furnace for protecting workmen in dismantling and making repairs to the furnace, without the necessity of cooling the furnace, whereby there is a material saving in time, and also preventing harm to workmen.

In accordance with the invention there is provided a supporting structure which may be in the form of a beam capable of being clamped or wedged between two buckstaves between which brickwork is to be taken down and built up, and associated with this beam are supports introducible into the furnace and held by the beam, while the supports, in turn, carry a frame on which are mounted slidable doors or shields so arranged as to be introduced into the furnace chamber and interposed between the interior of the furnace and workmen taking down and building a wall, thus protecting the workmen from serious burns or other injury and even from any marked discomfort.

The invention will be best understood from a consideration of the following detailed description taken in connection with the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claims.

In the drawings:—

Fig. 1 is an elevation showing a portion of the outer wall of a furnace with the shield structure in place.

Fig. 2 is a plan view of the mechanism shown in Fig. 1, but omitting any showing of the furnace itself.

Fig. 3 is a section on the line 3—3 of Fig. 1.

Fig. 4 is a section on the line 4—4 of Fig. 2, but on a larger scale.

Referring to the drawings, there is shown

a furnace 1 in the walls of which are buckstaves 2. No attempt is made to show any particular form or construction of furnace and mention is made of buckstaves only because these particular features of the furnace are utilized as a supporting means for a beam 3 which may be an iron or steel structure of any suitable form, either such as shown or of some other form. The respective ends of the beam carry screws 4 by means of which the beam may be tightly clamped by two adjacent buckstaves 2 at any desired height above the floor level. It will be understood, however, that while the screws 4 provide a convenient means for the purpose, other means may be employed for the same purpose.

Near the ends the beam 3 carries depending hooks 5 with hook ends 6 directed one toward the other. There are also provided elongated bars 7, each with a longitudinal slot 8 through a portion of its length and one end of each bar 7 has an extension 9 with a row of teeth 10 therealong. These teeth are in the form of ratchet teeth. Pivotally mounted on the beam between pairs of ears 11 are yokes 12, one near each end of the bar. The yokes in the particular structure shown are pivoted at their closed ends while their open ends are each connected by a pin 13 held in place by any suitable means, such as a cotter pin 14. The yokes 12 are in the nature of latches engaging suitable ones of the teeth 10 thereby holding the bars 7 when mounted upon the hook ends 6 of the pendant hooks 5, so that the bars 7 are approximately horizontal or in some other desired position. At the same time by releasing the bars 7 from the latches 12 these bars may be swung about the ends 6 of the hooks 5 as pivots or may be made to slide lengthwise of the hooks for a purpose which will hereinafter appear.

At the end of the bar 7 remote from the extension 9 is a lug or block 15 projecting from one face of the bar and this lug carries an adjustable hook 16.

There is also provided a frame 17 which may be of rectangular outline somewhat longer than wide but any particular shape is not obligatory, although an oblong rectangular frame is to be preferred. This frame may conveniently be made of pipe and in such case an opening 18 is made in the pipe at a high point so that the pipe may be filled

with water. Near the ends on those members of the frame which constitute the top and bottom in the installed position are hooks or guides 19 in which engage edge ribs or strips 20 of shields 21, 22 respectively. Extending lengthwise of the frame about midway between the top and bottom members is a bar 23 traversing eyes 24 on the respective shields 21 and 22. These eyes are arranged 10 in pairs near those ends of the shields which meet when the shields are brought together and the eyes of each pair are spaced apart a short distance to aid in supporting the shields but not interfering with sliding of 15 the shields toward and from each other along the middle guide bar 23, which latter, in the installed position, is about horizontal. The eyes 24 and hooks 19 provide convenient guides for the shields, which latter are offset 20 from the plane of the frame 17 so that they may slide beyond the end bars thereof. The bottom bar of the frame 17 is provided with a series of hooks 25 from which may be hung a curtain 26. The side bars of the frame 17 25 are provided with eyes 27 in which the hooks 16 engage and thus support the frame 17 with the shields 21 and 22 in an approximately upright position in the ordinary installation.

30 The bars 7 are long enough so that with the beam 3 outside of a wall of a furnace, the frame 17 may be tipped to an approximately horizontal position when the bars 7 are in a like position, and be withdrawn from the furnace when the front wall has reached about the height of the bars 7.

While the wall is being torn down or built, and especially in the latter event, the shields act as a protection for the workmen building 40 the wall so that the interior heat of the furnace will not directly reach them and the workmen are therefore protected from injury or even from undue heat. It is not necessary that the flames within the furnace 45 be put out, for, in the case of gas as a fuel the flames may burn to an extent which may be less than their full vigor. In the case of repairs it is not necessary to cool down the furnace, which operation consumes considerable time, and the loss of more time in reheating the furnace after repairs are made. When it is desired to work behind the buckstaves it is only necessary to slide the shields which may be made long enough to permit 50 such movement and protect workmen building walls between the buckstaves where they are too close together to install the beam 3.

55 The shields 20 and 21 are, of course, made of sufficiently refractory material to withstand the heat to which they are subjected and the same is true of the curtain 26.

What is claimed is:—

1. A shield structure for protecting workmen in repairing furnaces, comprising a support adaptable to extend into the furnace, 65

and a shield and carrier therefor adaptable to the support for location wholly within the furnace.

2. A shield structure for protecting workmen in repairing furnaces, comprising a supporting member adaptable and provided with means for fastening it to the furnace walls where the repair is to be made, and a shield and carrier therefor adaptable to and upheld by the support with the shield interior 70 to the furnace walls and movable with relation to the support for location wholly interior to the wall of the furnace in which the repairs are to be made.

3. A shield structure for protecting workmen when repairing hot furnaces, comprising a support adaptable to a furnace wall and extending between and clamped to the edge walls of a breach made through the furnace wall, other supports carried by the first 80 named support and movable thereon into the furnace interior to the breach, and a shield carried by the second named supports 85 in pendant relation thereto when in the interior of the furnace.

4. A shield structure for protecting workmen when repairing hot furnaces, comprising a support adaptable to a furnace wall and extending between and clamped to the edge walls of a breach made through the furnace wall, other supports carried by the first 95 named support and movable thereon into the furnace interior to the breach, and a shield carried by the second named supports in pendant relation thereto when in the interior 100 of the furnace, said shield being movable to either side of the breach.

5. A shield structure for protecting workmen when repairing hot furnaces, comprising a support adaptable to a furnace wall 105 and extending between and clamped to the edge walls of a breach made through the furnace wall, other supports carried by the first named support and movable thereon into the furnace interior to the breach, and a shield carried by the second named supports 110 in pendant relation thereto when in the interior of the furnace, said shield comprising slid able members movable to either or both sides of the edges of the breach. 115

6. A shield structure for protecting workmen when repairing hot furnaces, comprising a beam with clamping means at the ends for engaging adjacent buckstaves of the furnace, bars supported by the beam and 120 movable transversely thereof, and shields in turn carried by the bars in depending relation thereto and located within the furnace back of the wall to be repaired.

7. A shield structure for protecting workmen when repairing hot furnaces, comprising a beam with clamping means at the ends, said beam being of a length to engage adjacent buckstaves and be supported thereby, bars extending transversely of the beam 125 130

near the ends thereof and movable in the direction of their length into the furnace, shield devices, and a supporting frame for the shield devices carried by the inner ends 5 of the bars.

8. A shield structure for protecting workmen when repairing hot furnaces, comprising a beam with means for supporting it from upright members of the furnace, bars 10 carried by the beam and movable in the direction of their length transversely of the beam, said bars having pivotal connections with the beam, means for holding the bars in substantially horizontal positions, a frame 15 pendants supported by the inner ends of the bars, and shields carried by the frame.

9. A shield structure for protecting workmen when repairing hot furnaces, comprising a beam with means for supporting it 20 from upright members of the furnace, bars carried by the beam and movable in the direction of their length transversely of the beam, said bars having pivotal connections with the beam, means for holding the bars 25 in substantially horizontal positions, a frame pendants supported by the inner ends of the bars, and shields carried by the frame, said frame being of hollow construction and having means for introducing water 30 thereto.

10. A shield structure for protecting workmen when repairing hot furnaces, comprising a supporting beam with means for clamping it to and between spaced upright 35 parts of the furnace, bars carried by and rockable with relation to the beam and also 40 slideable in the direction of their length into and out of the furnace, and shield means carried by the inner ends of the bars.

11. A shield structure for protecting workmen when repairing hot furnaces, comprising a supporting beam with means for clamping it to and between spaced upright members of the furnace, bars carried by and 45 rockable with relation to the beam and also slideable in the direction of their length into and out of the furnace, shield means carried by the inner ends of the bars, said shield means comprising a frame, and shield devices 50 mounted to slide along the frame toward each other and also beyond the ends of the frame.

12. A shield structure for protecting workmen when repairing hot furnaces, comprising a supporting beam with means for clamping it to and between spaced upright 55 parts of the furnace, bars carried by and rockable with relation to the beam and also slideable in the direction of their length into and out of the furnace, shield means carried by the inner ends of the bars, said shield 60 means comprising a frame and shield devices mounted to slide along the frame toward each other and also beyond the ends of the frame, and said shield devices and

frame having coacting guiding means at the tops and bottoms of the shield devices and also at an intermediate point of the height of the shield devices.

13. A shield structure for protecting workmen when repairing hot furnaces, comprising a beam of a length to extend and be clamped between spaced parts of a furnace and to constitute the main support for the shield structure, supporting devices depending from the beam, bars each longitudinally slotted with the slot traversed by a supporting device from the beam, whereby the bar may be rocked and moved in the direction of its length transversely of the length of the beam, and each bar having ratchet teeth at one end, a latch for each bar carried by the beam and movable into engagement with a ratchet tooth to support the beam in a substantially horizontal position and projecting into the furnace, a frame carried by the inner ends of the bars in an upright position, and shields carried by and slideable lengthwise of the frame toward each other and beyond the ends of the frame. 90

14. A shield structure for protecting workmen when repairing hot furnaces, comprising a beam of a length to extend and be clamped between spaced parts of a furnace and to constitute the main support for the shield structure, supporting devices depending from the beam, bars each longitudinally slotted with the slot traversed by a supporting device from the beam, whereby the bar may be rocked and moved in the direction of its length transversely of the length of the beam, and each bar having ratchet teeth at one end, a latch for each bar carried by the beam and movable into engagement with a ratchet tooth to support the beam in a substantially horizontal position and projecting into the furnace, a frame carried by the inner ends of the bars in an upright position, and shields carried by and slideable lengthwise of the frame toward each other and beyond the ends of the frame, said shields and frame having coacting guiding means at the top and bottom. 100

15. A shield structure for protecting workmen when repairing hot furnaces, comprising a beam of a length to extend and be clamped between spaced parts of a furnace and to constitute the main support for the shield structure, supporting devices depending from the beam, bars each longitudinally slotted with the slot traversed by a supporting device from the beam, whereby the bar may be rocked and moved in the direction of its length transversely of the length of the beam, and each bar having ratchet teeth at one end, a latch for each bar carried by the beam and movable into engagement with a ratchet tooth to support the beam in a substantially horizontal position and projecting into the furnace, a 115 120 125 130

frame carried by the inner ends of the bars in an upright position, and shields carried by and slideable lengthwise of the frame toward each other and beyond the ends of the frame, said frame and shields having coacting guiding means at the top and bottom, the frame having an intermediate guide bar extending from end to end and the shields having guiding eyes traversed by the guide bar with the guiding eyes located close to the meeting edges of the shields.

16. A shield structure for protecting workmen when repairing hot furnaces, comprising a beam with means for clamping it

at different heights between fixed parts of the furnace structure, bars carried by the beam and extending into the furnace structure, a frame carried by the bars, shields carried by the frame, and a curtain also carried by the frame in depending relation thereto.

In testimony that I claim the foregoing as my own, I have hereto affixed my signature in the presence of two witnesses.

JAMES R. RISHEBEGAR.
